J. H. SPRAGUE,
FUR STRETCHER,
APPLICATION FILED MAY 5, 1920.

1,371,650.

Patented Mar. 15, 1921.

UNITED STATES PATENT OFFICE.

JAMES H. SPRAGUE, OF RIO BLANCO, COLORADO.

FUR-STRETCHER.

1,371,650.

Specification of Letters Patent.

Patented Mar. 15, 1921.

Application filed May 5, 1920. Serial No. 379,034.

To all whom it may concern:

Be it known that I, JAMES H. SPRAGUE, a citizen of the United States, residing at Rio Blanco, in the county of Rio Blanco 5 and State of Colorado, have invented certain new and useful Improvements in Fur-Stretchers, of which the following is a specification, reference being had to the accompanying drawings.

10 This invention relates to certain improvements in fur stretchers and has relation more particularly to a device of this general character especially designed and adapted for use in connection with cased 15 hides, and it is an object of the invention to provide a novel and improved device of this general character of an expandible type and wherein means are provided for effectively locking the device in its various adjustments as occasioned by the necessities of 20 practice.

The invention consists in the details of construction and in the combination and arrangement of the several parts of my 25 invention, whereby certain important advantages are attained and the device rendered simpler, less expensive and otherwise more convenient and advantageous for use, as will be hereinafter more fully 30 set forth.

The novel features of my invention will hereinafter be definitely claimed.

In order that my invention may be the better understood, I will now proceed to 35 describe the same with reference to the accompanying drawings, wherein:

Figure 1 is a view in elevation of a fur stretcher constructed in accordance with an embodiment of my invention;

40 Fig. 2 is a view partly in elevation and partly in section of the stretcher as herein embodied, the section being taken substantially on the line 2—2 of Fig. 1;

Fig. 3 is an enlarged fragmentary sectional view taken substantially on the line 45 3—3 of Fig. 1; and

Fig. 4 is an enlarged fragmentary sectional view taken substantially on the line 4—4 of Fig. 2.

50 As disclosed in the accompanying drawings, 1 denotes an elongated rod preferably metallic and with which is adjustably engaged the slides S and S'. The slide S comprises a flat metallic plate 2 provided at one end portion with the loop 3 through 55 which the rod is slidably engaged and adja-

cent its opposite end portion with the transversely spaced lugs or brackets 4. Pivots engaged between the lugs or brackets 4 is a cam 5 having its working face 6 serrated so that said cam will have effective locking engagement with the rod 1 to hold the slide S against movement longitudinally of the rod and in a desired position thereon. The cam 5 is also provided with the tail piece 65 or handle 7 in order to facilitate the moving of said cam into either working or inoperative position.

Extending laterally in opposite directions from the slide S and pivotally engaged therewith, as at 8, substantially midway of the slide S are the rigid arms or links 9. The inner end portion of the slide S or more particularly the plate 2 thereof has pivotally engaged therewith, as at 10, the inner end portions of the oppositely directed rigid arms or links 11, said arms or links 11 being substantially at right angles to the arms or links 9.

The slide S' also comprises a plate 12 provided adjacent its inner end portion with the loop 14 through which the rod is loosely disposed and the opposite end portion of the plate is provided with the transversely spaced lugs or brackets 15 between which is pivotally engaged the cam 16 provided with a serrated periphery and which cam is adapted to have a gripping action upon the rod 1 to hold the slide S' in desired position longitudinally of the rod. The cam 16 is also provided with an operating tail or handle 17.

Substantially midway thereof, the plate 12 has pivotally engaged with the side marginal portions thereof the rigid links or arms 18 and the outer ends of said arms or links 18 are also pivotally engaged, as at 18', with the elongated and substantially rigid members or arms 20 at a slight distance inwardly of the adjacent ends of said rigid members or arms 20. The opposite end portions of said arms 20 are pivotally engaged, as at 20', with the outer or free extremities of the arms or links 11, hereinbefore referred to. The arms or links 18 serve as braces to hold said arms 20 out against the fur to be stretched when my improved device is in applied position. Pivotally engaged with each of the arms 20 and preferably at the pivotal connection 18' is a substantially rigid arm or link 21. The opposite end portion of said link or arm 21 is

provided with an angularly disposed lug or foot 22 provided with an opening 23 through which opening the rod 1 is loosely disposed. The lugs or feet 22 are engaged 5 with the rod 1 outwardly of the slide S'.

Pivottally engaged with the outer end portions of each of the links or arms 9 is an end portion of an elongated and substantially rigid member or arm 19. The opposite end 10 portions of the arms 19 are pivottally engaged, as at 24, with the rod 1 at a point outwardly of the feet 22 of the arms or links 21.

After my improved stretcher has been 15 properly inserted within a cased hide, the slides S or S' are properly adjusted longitudinally of the rod 1 to cause the members or arms 19 and 20 to properly engage the hide whereupon said slides will lock against 20 movement. My improved stretcher can be employed in connection with hides of different sizes. By forcing the slide S inwardly of the rod 1, the stretcher can be contracted for an effective use in connection with small 25 furs, such as mink. The arrangement shown in the accompanying drawing is particularly adapted for use in connection with coyote furs. By removing the pivotal connection 18', the stretcher can be effectively 30 employed in connection with the furs of foxes, skunks, or the like.

It is also to be particularly noted at this time that the rod 1 is angular in cross section so that the slides S and S' are maintained 35 against rotary movement around said rod 1.

From the foregoing description, it is thought to be obvious that a fur stretcher constructed in accordance with my invention 40 is particularly well adapted for use by reason of the convenience and facility with which it may be assembled and operated, and it will also be obvious that my invention is susceptible of some change and modification 45 without departing from the principles and spirit thereof, and for this reason I do not wish to be understood as limiting myself to the precise arrangement and forma-

tion of the several parts herein shown in carrying out my invention in practice except 50 as hereinafter claimed.

I claim:

1. In a stretcher of the class described, a central elongated rod, a plurality of longitudinal rods associated with said elongated 55 rod and arranged in pairs in intersecting planes and means connecting said elongated rod and said longitudinally extending rods for independently adjusting the ends of said longitudinally extending rods with relation 60 to said central elongated rod.

2. In a stretcher of the class described, an elongated rod, a pair of spaced slides mounted upon said rod adjacent the ends thereof for longitudinal movement thereon and independently adjustable with relation thereto, means for independently locking said slides in an adjusted position, a pair of opposed elongated members arranged upon opposite sides of said rod and pivotally connected with said rod adjacent one end thereof, links connecting the free ends of said rods with the slide arranged adjacent the opposite end of said rod, a second pair of opposed elongated members associated with 75 said elongated rod and disposed in a plane at right angles to the plane of the first mentioned arms, links pivotally connected with one of said slides and with the adjacent ends of said last mentioned elongated members, 80 and links pivotally connected with the other of said slides and with the last mentioned elongated members adjacent the opposite end thereof.

3. In a stretcher of the class described, an 85 elongated rod, a plurality of opposed pairs of elongated members disposed radially about said rod and in spaced relation to one another and means operatively connecting said rod and said members whereby said 90 members may be adjusted with relation to said rod.

In testimony whereof I hereunto affix my signature.

JAMES H. SPRAGUE.
